SHOE MARKING MACHINE

Benjamin W. Freeman, Cincinnati, Ohio, assignor
to The Louis G. Freeman Company, Cincinnati,
Ohio, a corporation of Ohio

Application October 4, 1930, Serial No. 486,437

19 Claims. (Cl. 33—4)

My invention relates to shoe marking machines, and particularly to a machine adapted for shoe upper back seam height marking.

In the lasting of shoes there has been no definite method by which the operator can know exactly at what point, along the back seam particularly, he desires to turn the shoe upper over to tack it to the last. Ordinarily the operator gauges by eye, and estimates the desired height of the back seam of the upper, and then turns over what he considers is the proper amount and tacks the turned over bottom edge of the upper to the last.

Without some definite mark on the shoe upper along the back seam either to indicate the desired height of the back seam or the desired amount to be turned over, irregularities in workmanship often result.

It is the object of my invention to provide a marking machine provided with means by which the operator can definitely indicate the material which he desires to turn over and tack to the last. It is a further object of my invention to provide a support for the shoe upper along the back seam, and to provide gauging and marking instrumentalities in which the marking device is so constructed and arranged that it will follow the lateral contour of the shoe upper.

In a machine of this type it is further my object to provide an adjustable marking device which can be set for a desired thickness of shoe upper so that the upper will not be injured by too deep or non-uniform marking and will yet be so thoroughly marked that an operator can easily observe the line on which he desires to turn over the lower edge of the upper and secure it to the last.

The above objects and other objects to which reference will be made in the ensuing disclosure, I accomplish by that certain combination and arrangement of parts of which I have illustrated a preferred embodiment, with several modifications indicating various ways in which the dimensions of the turned over part of the upper which is to be secured to the last may be indicated.

Referring to the drawings:—

Figure 1 is a front elevation from the pad end showing a preferred construction of marking machine with the marker in mid position.

Figure 2 is a side elevation of the machine.

Figure 3 is a plan view of the marking device.

Figure 4 is a detail showing a modified type of gauging device.

The machine is ordinarily mounted on a suitable table or standard 1 and is composed of a frame having a base portion 2, with an elevated column 3 in which is rotatably mounted a shaft 4. A crank arm 5 may be suitably connected to a rod 6 extending below the machine and adapted to be operated by any suitable means, as by a foot treadle 7, pivoted at 7a on the floor 7b as diagrammatically shown in Figure 1. The shaft 4 may be lubricated by means of an oil cup 8. On the end of the shaft opposite the crank 5 I have shown the marking arm 9, which is channeled out as indicated at 10 and in the channel a slider 11 is urged downwardly by means of a spring 12. Within the channeled portion 10 I have shown a block 13, and the slider 11 has at its upper end a rod 14 which passes through the block 13. A cover plate 15, which may be secured to the arm 9 with screws 16, encloses the slider 11 and limits it to an up and down reciprocating movement. The slider 11 has arms 17 between which is journaled a marking disc 18. The slider has an extension 19, and a thumbscrew 20 may be employed to limit the downward movement of the slider and consequently of the marking disc 18. The thumbscrew 20 may be set in the desired position by means of a lock screw 21. The arm 9 is fixedly mounted on the shaft 4 as with a pin indicated at 22.

A horn 23, suitably contoured to support the back seam of an upper such as is indicated in dotted lines at 24 in Figure 2, has a shaft 35 portion 25 which extends through a hole in the base 2 and which may be secured in a desired adjusted position with a lock screw 26. A gauge bar 27, having a flanged end 28, slides under a plate 29 having a slot 29' within a channeled 40 portion of a block 30 which plate and block are secured to the base 2 as by means of screws.

For moving the gauge bar 27 to a desired position I have provided a shifting arm 31 pivoted as indicated at 32. The arm 31 has an extension with a slot 33, and a block 34 is secured to the arm 27 by a screw 35. This block 34 is shorter than slots 29' and 33. The machine has graduations 36, and the handle member has a sharp edge 37 which rides over these graduations. It will be obvious that when the handle 31 is moved counterclockwise, as shown in the plan view in Figure 3, the flanged end 28 of the gauge is advanced towards the shoe upper support 23.

For inking the marking disc and supplying a constantly changing marking surface on the pad I have mounted a circular pad 38 on a spindle 39. The spindle 39 is journaled in a boss 40 which forms part of a member having a spindle 42 journaled in a boss 43. The shaft 42 may be secured in desired adjusted position in the boss by means of a set screw 44. A block 45 is secured to the spindle member 42 inclin- 10 ing to the rear of the machine and also toward the horn 23, and on this block 45 a pivoted pawl 46 is mounted, correspondingly inclined. The pawl has a tooth 47 which engages the ratchet teeth 48 of the circular member carrying the pad. A spring 49 returns the pawl to its normal position against stop pin 50a. The end 50 of the pawl opposite the pawl tooth is engaged by a rocker 51 pivoted in the pedestal as indicated at 52. The rocker 51, has an upwardly extending arm 53 which with the movement of the arm 9 across the path and across the shoe upper, is engaged, to rock the rocker 51 and operate pawl 46, by a rod 54 which extends from the boss 55 of the arm 9. The hooked end of rocker arm 53 limits the movement of the arm 9. A locking pawl 56 pivoted on the block 45 and affected by the spring 57, prevents the ratchet 48a from rotating in a non-feeding direction, and as the pad is rotated by pawl 46 under action of rocker 51, a constantly renewed inking surface is provided for the inking disc.

In the example of the machine shown in Figures 1 to 3, the upper 24 is positioned on the horn along the top curved surface thereof, and the upper edge of the back seam placed against the flanged end 28 of the gauge. The disc marker will then indicate a predetermined height of back seam, and if the operator of the machine places the marked line at the bottom edge of the last and turns the upper over on the line, a very accurate regulation of the height of the back seam may be obtained.

As a modified type of arrangement in Figure 4 I have indicated details of the machine in which, instead of gauging the height of the back seam, I provide means for gauging the amount of the upper which is to be turned over and lasted. The horn 23a has a contoured support and a flattened surface 58 on which I have shown a slidably adjustable gauge 59 having a lot 60 therein which enables the flanged end 61 of the gauge to be moved to a position in which it may be set by means of the set screw 62, which has a shank 63 which engages a threaded hole in the horn. In using the modification shown in Figure 4 a mark may be placed on the upper which corresponds to the mark provided with the other method of gauging, but in this instance the gauged dimension will be the amount of the upper to be turned over in the lasting.

In Figure 4 I have further indicated a heating unit 64 which may be mounted on the arm 9 and by which the marking instrument may be heated if desired so as to form a more distinct line to indicate the line at which the upper is to be turned over in the lasting operation or to use marking or impression material requiring the use of heat for proper impressions.

A particular feature of my machine of great importance is the resilient mounting for the slider carrying the marking device which enables the marking instrument not only to mark

a line along the back seam, but to follow the contour for any desired distance, which enables me to mark a shoe upper with a line which will be easy to follow in the lasting operation, and in the application of which there will be no tendency to mar the shoe upper. 5

Having thus described my invention, what I claim as new and desire to secure by Letters Patent, is:—

1. A back seam height marking machine having a curved support for supporting a shoe upper with the back seam thereof exposed thereon, marking means movable in a curved line over said support said line conforming in curvature to the curve of the support, said marking means mounted on a member movable in an arc opposed to the curve of the support, and having a resiliently mounted marking edge carried on said member permitting said edge to move in a curve corresponding to the arc of the support and gauging means associated with said support for gauging the desired height of the back seam. 10

2. A back seam height marking machine having a curved support for supporting a shoe upper at the back seam thereof, marking means movable in a curved line over said support said line conforming in curvature to the curve of the support, said marking means mounted on a member movable in an arc opposed to the curve of the support, and having a resiliently mounted marking edge carried on said member permitting said edge to move in a curve corresponding to the arc of the support and gauging means associated with said support for gauging the desired width 30 of upper to be turned over and secured to the last. 35

3. A back seam marking device having a curved support for supporting a correspondingly curved shoe upper at the back seam thereof, marking means movable over the surface and in a curved line conforming in its curvature to the shape of said support, said marking means mounted on a member movable in an arc opposed to the curve of the support, and having a resiliently mounted marking edge carried on said member permitting said edge to move in a curve corresponding to the arc of the support and gauging means associated with said support for indicating a desired position on the back seam 50 of a shoe upper to which a mark is to be applied. 45

4. A back seam marking device having a curved support for supporting a correspondingly curved shoe upper at the back seam thereof, marking means movable over the surface and in a curved line conforming in its curvature to the shape of said support, said marking means mounted on a member movable in an arc opposed to the curve of the support, and having a resiliently mounted marking edge carried on said 55 member permitting said edge to move in a curve corresponding to the arc of the support and gauging means associated with said support for indicating a desired position on the back seam of a shoe upper to which a mark is to be applied, 60 said gauging means being adjustable. 65

5. A marking machine having a curved support for a correspondingly curved shoe part to be marked, and marking means movable over the surface and in a line corresponding in curvature to the shape of the support at least over part of the curve of the support, said marking means mounted on a member movable in an arc opposed to the curve of the support, and having a resiliently mounted marking edge carried on 70 75

- said member permitting said edge to move in a curve corresponding to the arc of the support said marking means comprising a rotary disc having a peripheral marking edge, and means 5 providing a constantly changing ink applying surface, adapted for contact with said marking edge, and means for limiting the movement of said marking means.
6. In a shoe upper marking machine a relatively fixed support having a curved surface corresponding to the curve of the back seam of a shoe upper, a gauge adjustably mounted so as to determine the distance which a shoe upper may be extended on said support, and marking means 10 movable so as to traverse the curved surface of said support, said marking means mounted on a member movable in an arc opposed to the curve of the support, and having a resiliently mounted marking edge carried on said member permitting 15 said edge to move in a curve corresponding to the arc of the support and means adapted to contact with said marking edge for supplying a fresh supply of marking material to said marking edge.
- 20 7. In a machine for marking shoe uppers, means for gauging the position on which a mark is to be applied to a shoe upper, a support contoured to the shape of a shoe part to be supported thereon, and marking means mounted for movement over said support in a curved line corresponding to the contour of said support, said marking means mounted on a pivoted arm and means including a treadle for operating said arm, and said marking means comprising a 25 rotatable disc journaled in a slider on said pivoted arm, and resilient means for urging said slider toward said support.
- 30 8. In a machine for marking shoe uppers, means for gauging the position on which a mark is to be applied to a shoe upper, a support contoured to the shape of a shoe part to be supported thereon, and marking means mounted for movement over said support in a curved line corresponding to the contour of said support, said marking means mounted on a pivoted arm and means including a treadle for operating said arm, and said marking means comprising a 35 rotatable disc journaled in a slider on said pivoted arm, and resilient means for urging said slider toward said support, and means for limiting the movement of said slider toward said support.
- 40 9. A marking machine having a curved support for a correspondingly curved shoe part to be marked, and marking means movable over the surface of the support and in a line corresponding in curvature to the shape of the support at least over part of the curve of the support, a member pivoted at a point remote from said support and whereon said marking means is mounted so as to be movable with the member and normally in an arc opposed to the curve of the support, said marking means being resiliently mounted on said member, thereby permitting said means to be moved by contact with the shoe part on the support in a curve corresponding to an arc of curvature of the support, and treadle means for actuating said pivoted member.
- 45 10. A marking machine having a curved support for a correspondingly curved shoe part to be marked, marking means movable over the surface of the support and in a line corresponding in curvature to the shape of the support at least over part of the curve of the support, a member pivoted at a point remote from said support and whereon said marking means is mounted so as to be 50 movable with the member and normally in an arc opposed to the curve of the support, said marking means being resiliently mounted on said member, thereby permitting said means to be moved by contact with the shoe part on the support in a curve corresponding to an arc of curvature of the support, and means operatively connecting said marking element and said operating means for relative movement, whereby said marking means may follow said curvature.
- 55 11. A marking machine having a curved support for a correspondingly curved shoe part to be marked, and marking means comprising a rotary disc movable over the surface of the support and in a line corresponding in curvature to the shape of the support at least over part of the curve of the support, a member pivoted at a point remote from said support and whereon said marking means is mounted so as to be movable with the member and normally in an arc opposed to the curve of the support, said marking means being resiliently mounted on said member, thereby permitting said means to be moved by contact with the shoe part on the support in a curve corresponding to an arc of curvature of the support.
- 60 12. A marking machine having a curved support for a correspondingly curved shoe part to be marked, marking means comprising a rotary disc movable over the surface of the support and in a line corresponding in curvature to the shape of the support at least over part of the curve of the support, a member pivoted at a point remote from said support and whereon said marking means is mounted so as to be movable with the member and normally in an arc opposed to the curve of the support, said marking means being resiliently mounted on said member, thereby permitting said means to be moved by contact with the shoe part on the support in a curve corresponding to an arc of curvature of the support, and means providing a changing ink applying surface adapted to contact with the edge of the disc.
- 65 13. A marking machine having a curved support for a correspondingly curved shoe part to be marked, marking means movable over the surface of the support and in a line corresponding in curvature to the shape of the support at least over part of the curve of the support, a member pivoted at a point remote from said support and whereon said marking means is mounted so as to be movable with the member and normally in an arc opposed to the curve of the support, said marking means being resiliently mounted on said member, thereby permitting said means to be moved by contact with the shoe part on the support in a curve corresponding to an arc of curvature of the support, and treadle means for actuating said pivoted member.
- 70 14. A marking machine comprising a convex curved support to the curvature of which the curved back seam part of a shoe upper may be conformed, a marking element to move across said support and be guided by the shoe upper part around the curvature thereof for a slight distance at each side of the back seam, operating means having a movement in a path fixed relative to said support but irrespective of said curvature, and means operatively connecting said marking element and said operating means for relative movement, whereby said marking means may follow said curvature.
- 75 15. A marking machine comprising a curved support to the curvature of which the curved back seam part of a shoe upper may be con-

- formed, a marking element to move across said support and be guided by the shoe upper part around the curvature thereof, operating means having a movement irrespective of said curvature, means operatively connecting said marking element and said operating means for relative movement, whereby said marking means may follow said curvature, and adjustable means for variably limiting the curve following movement of said marking means.
16. A marking machine comprising a curved support to the curvature of which the curved back seam part of a shoe upper may be conformed, a holder having a surface to support marking material, a marking element to move across said support and said holder surface and be guided by the shoe upper part around the curvature thereof and by said holder surface, operating means having a movement irrespective of said curvature, means operatively connecting said marking element and said operating means for relative movement, whereby said marking means may follow said curvature and said holder surface.
17. A marking machine comprising a curved support to the curvature of which the curved back seam part of a shoe upper may be conformed, a holder having a surface to support marking material, a marking element to move across said support and said holder surface and be guided by the shoe upper part around the curvature thereof and by said holder surface, operating means having a movement irrespective of said curvature, means operatively connecting said marking element and said operating means for relative movement, whereby said marking means may follow said curvature and said holder surface, and adjustable means for variably limiting the curve following movement of said marking means.
18. A marking machine comprising a convex curved support to the curvature of which the curved back seam part of a shoe upper may be conformed, a member pivoted to swing across said support in a fixed path relative thereto, and a marking element movable on said member to be guided by the shoe upper part around the curvature thereof for a slight distance at each side of the back seam as said member swings across the support.
19. A marking machine comprising a curved support to the curvature of which the curved back seam part of a shoe upper may be conformed, a member pivoted to swing across said support, a marking element movable on said member to be guided by the shoe upper part around the curvature thereof as said member swings across the support, a rotatable holder having a surface to support marking material adjacent to said support, said member swinging said marking element into contact with said surface, and ratchet means operated by the swinging of said member to rotate said holder.

BENJAMIN W. FREEMAN.
